UNITED STATES PATENT OFFICE.

WILLIAM P. CRARY, OF NEW YORK, N. Y.

DESIGN FOR A BOTTLE.

SPECIFICATION forming part of Design No. 18,520, dated August 14, 1888.

Application filed June 21, 1888. Serial No. 277,833. Term of patent 7 years.

To all whom it may concern:

Be it known that I, WILLIAM P. CRARY, of the city, county, and State of New York, have invented a new and original Design for a Bottle, 5 of which the following is a full, clear, and exact specification.

My newly-designed bottle is fully illustrated in the accompanying drawing, to which reference is made.

10 The body A of the bottle is circular in cross-section and tapers from the base B to the neck C—that is, the outside lines *a b* converge, approaching nearer together from the bottom toward the top of the bottle. The neck C is 15 circular in cross-section, and is of the reverse taper to that of the body A—that is, its lines *c d* approach nearer together from the top

downward and are at a reverse angle to that of the lines of the body A. The body A joins the neck C by a curved breast, D, as shown 20 clearly in the drawing. The base B is circular in outline, and is of greater diameter than the body A, forming an annular offset, *e*, at the juncture of the body A with the base.

I claim—

25 The design for a bottle herein shown and described, the same consisting of the tapering body A, enlarged base B, curved breast D, and tapering neck C, the lines of which are at a reverse angle to the lines of the body A. 30

WILLIAM P. CRARY.
